United States Patent

Des. 241,597
Patented Sept. 28, 1976

241,597

FUNNEL

Raymond C. Confer and Douglas C. Confer, Gasport,
N.Y., assignors to Confer Plastics Inc.

Filed Jan. 15, 1975, Ser. No. 541,220

Term of patent 14 years

Int. Cl. D7—99

U.S. Cl. D7—68

Fig. 1.

Fig. 2.

Fig. 3.

Fig. 4.

FIG. 1 is a top perspective view of a funnel showing our new design;

FIG. 2 is a side elevational view;

FIG. 3 is a top plan view; and

FIG. 4 is a bottom plan view.

All side elevational views of the funnel are identical to that illustrated in FIG. 2.

We claim:

The ornamental design for a funnel, as shown and described.
